RESPIRATOR FACE MASK

Robert Hans Muller, Abbots Langley, England, assignor
to J. G. Franklin & Sons Limited, Dalston, London,
England

Filed June 2, 1958, Ser. No. 51,140

Term of patent 14 years

Claims priority, application Great Britain Dec. 9, 1957

(Cl. D83—1)

Fig. 1 is a front perspective view of a respirator face mask showing my new design;

Fig. 2 is a left side elevational view thereof;

Fig. 3 is a rear perspective view thereof;

Fig. 4 is a front elevational view thereof;

Figs. 5 and 6 are top and bottom plan views, respectively; and

Fig. 7 is a rear elevational view of the mask.

I claim:

The ornamental design for a respirator face mask, substantially as shown.
